AUTOMATICALLY STEPPED POCKET PUNCH

John Kertes, Pittsburgh, Pa.

Application August 18, 1947, Serial No. 769,127

6 Claims. (Cl. 164—89)

1

This invention relates to punching apparatus usable as a check protector, or protective check writer.

One object of the invention is to provide a check protector, or writer, which is accurate in its punching operation and in the alignment of its punching, which is simple and easy to operate, and which is of such simple and compact construction that it is particularly suitable for individual ownership and use throughout any of the variations in size and adaptation of which it is susceptible.

Another object of the invention is to provide a check protector, or writer, which provides means for aligning a check in position to receive a series of perforated digits and symbols, and which provides in conjoint assembly means for selecting, positioning and aligning digits or symbols, and for moving a check through appropriately spaced intervals to receive such perforations.

Another object of the invention is to provide a check protector, or writer, having the above-noted desirable properties, which is so small and compact that it conveniently can be carried in a pocket or purse.

Another object of the invention is to provide a check protector, or writer, including automatic means for moving a check therethrough at appropriately spaced intervals.

Still another object of the invention is to provide punching apparatus of the above-noted simple, compact and easily operable sort, which while primarily intended for the protective writing of checks is capable of being used, or of obvious modifications for use, in punching dates and for other punching operations.

In the accompanying drawings, exemplary of an embodiment of my invention:

Fig. I is an elevational view of my check protector or writer illustrating certain of the parts in operating position and a protecting closure clip or guard provided for the lower portion of the check protector when not in use.

Fig. II is an elevation of the check protector with one side thereof and the clip removed to expose the operating elements within the casing, said parts being shown in inoperative position.

Fig. III is an enlarged cross-sectional view taken in the plane of the section line III—III of Fig. I.

Fig. IV is an enlarged cross-sectional view taken in the plane of the section line IV—IV of Fig. I.

Fig. V is an enlarged fragmentary detail view illustrating the check moving rollers and associated ratchet mechanism in side elevation.

2

Fig. VI is an enlarged fragmentary horizontal sectional detail view through the punching wheel showing the guiding element for the punching wheel in plan and in the same relative position as in Fig. II.

Fig. VII is a front elevation of the structure shown in Fig. VI.

Fig. VIII is a bottom plan view, showing the true bottom wall of the casing, certain of the lower parts of the protector being removed.

Fig. IX is an enlarged fragmentary perspective view of the lost motion connection between the pawl and the operating arm.

Fig. X is a view similar to Fig. V illustrating a modification of the check moving structure.

The punching assembly of the apparatus comprises a punching wheel carrying peripherally thereof punching characters which is mounted for vertical movement in the casing, means for rotating the punching wheel to bring a selected character on the wheel into punching position, operable means for moving the punching wheel in the punching action, resilient means arranged yieldingly to oppose movement of the punching wheel in its punching action, and means for guiding the travel of the punching wheel in its punching movement. Desirably and as herein disclosed, the punching assembly comprises also means for indicating to a user the adjustment of the punching wheel, and the resilient means acts to return the punching wheel from the limit of its printing movement to its adjusting position.

This assembly I further have organized in such way that the several necessary or desirable functions are performed positively and with a high order of accuracy by elements which are so formed and inter-engaged that the overall dimensions of the assembly are reduced to a minimum. In the illustrated embodiment of my invention the punching elements of the assembly are characters formed by spaced groups of perforating pins on the periphery of the punching wheel.

In combination with the punching assembly, I have further provided a means for automatically moving the check, or other piece of paper, to accurately space the punching of the individual characters, said means being operated by the means for moving the punching wheel in the punching operation. Additionally, or alternatively, manual means for moving the check, or other piece of paper, to properly space the punching of the individual characters may be provided.

Specifically as shown in the accompanying drawings, the reference numeral 1 indicates the main body of the casing which may be formed of

metal, plastic, or any other suitable material. As shown, the smallest dimension of the casing is its transverse dimension, closely to embrace the punching wheel of the assembly and to economize in the overall dimensions of the device. In both side walls $1a$ of the casing there are vertically elongate slots 2 through which project trunnions 3 centrally integrated with punching wheel 4 . These trunnions 3 which project through the slots 2 in the casing side walls pass also through holes 5 in arms 6 mounted for reciprocation in suitable recesses 7 in the side walls $1a$. Trunnions 3 may be integrated with wheel 4 in any suitable manner as by being the terminals of a shaft keyed in the wheel or by being cast or pressed of one piece with the wheel.

An operating element or arm 8 is pivotally connected or hinged to the upper forward edge portions of the side walls $1a$ as by means of a pin 9 . The arm 8 extends substantially the entire length 20 of the casing 1 and is of a width substantially equal to the spacing of the side walls $1a$, whereby it provides a closure, or partial closure or top wall of the casing.

The arms 6 which produce longitudinal movement of the punching wheel 4 are pivotally connected to the arm 8 as by means of a pin 10 at a point rather closely adjacent the pivot pin 9 of the arm 8 . This causes the distal or free end of the arm 8 to have a relatively great movement 30 with respect to the movement of the punching wheel 4 .

The rearward wall $1b$ of the casing is preferably, but not necessarily, a block-like element having in general a thickness equal to the space 35 between the side walls $1a$ and extending forwardly to a position adjacent the punching wheel 4 . The upper end $1c$ of the wall $1b$ terminates at a point below the upper edges of the side walls $1a$ and functions as a stop to limit the downward 40 movement of the operating arm 8 between the said side walls, and as a socket for receiving the operating arm in nested position.

A recess 11 is provided in the top $1c$ of the rear wall $1b$ and suitably mounted in said recess is a conical coil spring 12 which is also connected to the arm 8 in any suitable manner.

In the punching action, pressure is exerted on operating element 8 to move it downwardly against the resistance of spring 12 . In this downward movement the operating element by engagement of the arms 6 with the trunnions 3 of the punching wheel carries the punching wheel downwardly, this movement being permitted by the elongate form of the slots 2 through which the trunnions project. The return movement is effected under the influence of spring 12 bearing upwardly against the operating element 8 .

In its structure punching wheel 4 may be made in any suitable manner and constructed of any suitable material, but as shown, is of solid construction such as results from the casting or pressing of aluminum or other suitable relatively light metal, metallic alloy or plastic. Along one peripheral edge, punching wheel 4 is beveled to provide a shoulder 13 having therein relatively shallow notches 14 . Aligned with notches 14 , the adjacent side face of the wheel has therein radial slots 15 which extend to the peripheral face of the wheel and serve as guide slots for the punching movement in the manner which will be described.

On the periphery of the punching wheel and appropriately positioned thereon with respect to guide slots 15 there are a plurality of groups 75 of

perforating pins, the pins of each group being arranged to form a digit, letter or symbol. The punching movement and return movement of wheel 4 are guided by means of an L-shaped resilient guide member 17 , which is secured to the inner surface of the adjacent side wall $1a$ of the casing. The angularly extended leg, or flange, $17a$ of this flat resilient element rides on the shoulder 13 of the punching wheel when the wheel is in its upward or adjusting position and successively and yieldingly engages notches 14 in the shoulder of the wheel when the wheel is rotated. When rotation of the wheel ceases with the angular leg or flange $17a$ in one of the notches 14 , the wheel is directed upwardly or downwardly in a straight line by engagement of this leg, or flange, in the slot 15 of the wheel which is aligned with that notch.

It will be noted in Figs. I, III and VIII of the drawings that a disc 18 is applied to one of the trunnions 3 of the punching wheel and this disc, which serves as an indicator as well as means for rotating the punching wheel, carries both on its face and on its periphery a plurality of characters which may be digits, symbols or letters. Disc 18 is rigid with wheel 4 , and the characters appearing on its face are so arranged with respect to the groups 16 of the pins on the periphery of the punching wheel that when one of those characters is in an indicated position, the corresponding group of pins for punching that character is in position to be effectively registered upon downward punching movement of wheel 4 . In making the adjustment, disc 18 is rotated, rotating the punching wheel and this rotation from character to character is indicated as audible clicks and by yielding resistance to rotation, as guiding flange $17a$ of guide member 17 enters successive notches 14 of the wheel. When disc 18 indicates that the proper character is presented for registry, downward pressure on operating element 8 performs the punching operation; the wheel being guided in its downward movement, as above described, by engagement of guide flange $17a$ in the appropriate slot 15 of the punching wheel.

As shown in Fig. VIII of the drawings, the bottom wall $1d$ of the casing has a perforate grid 19 , the holes 20 through which are so arranged as to permit the passage of the pins of all the several groups 16 carried on the periphery of the punching wheel, so that the pins projected through grid 19 can perforate a sheet of paper or the like which is presented for punching.

A downwardly directed, channel-retaining plate 21 is secured at one of its ends in any suitable manner to a lower face $1e$ of a portion of the rearward wall $1b$ which depends slightly below the bottom wall $1d$ of the casing as illustrated in Fig. V. The other end of the retaining plate is free so that a piece of paper such as a check may be slipped between the retaining plate and the bottom wall of the casing. This retaining plate has therein a grid 22 the perforations of which register with the perforations of grid 19 formed in the bottom wall of the casing. In the punching operation the check, or other sheet of paper, lies between the bottom $1d$ of the casing and the retaining plate 21 . The perforating pins therefore pass through the perforations of grid 19 of the casing and into the perforations in grid 22 of the retaining plate. When the pins are retracted, retaining plate 21 and its grid 22 counteract any tearing tendency which the pins otherwise might exert on the paper.

Retaining plate 21 serves to position the check, or other sheet of paper, for the punching operation. For check writing, however, and even for other punching operations, it is useful to provide means which assist the user in accurately determining the positioning of a line of punching which is to be made and in accurately spacing the punching of the individual characters. Such adjusting means consists primarily of a pair of rollers, one of which is a live roller and the other an idler roller, and means to actuate the live roller in a step by step movement.

Referring to Figs. II, IV, V and IX, the adjusting means will be seen to comprise an elongate live roller 23, preferably made of rubber, positioned below the forward lower edge portion 1f of the rear wall 1b, said forward lower edge portion of the wall being suitably spaced above the bottom wall 1d of the casing. An L-shaped bracket 24 is suitably secured to the edge 1f and the depending leg 25 thereof provides a bearing for one end of the shaft 26 to which the roller 23 is rigidly secured in any desirable manner. The other end of the shaft 26 is journaled in a forward edge 1g of the rear wall 1b. Also rigidly connected with the shaft 26 rearwardly of the roller 23, is a ratchet wheel 27, comprising teeth in this instance, in the nature of a three lobed cam. A pawl 28 for actuating the ratchet wheel extends upwardly of the casing in a suitable recess 29 provided in the wall 1d.

As illustrated in Fig. IX, an upper end portion 30 of the pawl 28 is reduced in width to provide spaced shoulders 31 and 32 and this portion 30 of the pawl 28 is embraced by a short transmitting arm 33 pivotally connected to operating arm 8 as by means of a pin 34 extending through opening 35. The embracing portion or saddle 36 of the transmitting arm 33 is substantially shorter than the distance between the shoulders 31 and 32 on the pawl 28 to provide a lost motion connection between the pawl and the operating element 8. This lost motion connection is such as to provide sufficient lost motion that the perforating pins on the punching wheel are disengaged from the paper before the pawl 28 is actuated to rotate the ratchet 27 and roller 23 to step the paper along. Similarly, downward movement of pawl 28 into position behind a tooth of ratchet wheel 27 is accommodated to the difference in the length of movement of the punching wheel and the portion of the operating arm to which the pawl is attached by this lost motion connection.

A spring 33a secured to the adjacent wall 1a of the casing holds the pawl 28 in contact with the ratchet wheel 27, and a resilient brake or locking element 37 mounted on the inner wall 29a of the recess 29 prevents reverse movement of the ratchet wheel.

The roller 23 projects slightly below the lower wall 1d of the casing through a suitable opening 38 to contact an elongate idler roller 39, preferably also of rubber, projecting upwardly through an opening 40 provided in the retaining plate 21. The roller 39 is rotatably mounted on resilient bracket members 41 secured to the web portion of an upwardly directed channel member 43 frictionally received or otherwise suitably secured within the channel retaining plate 21.

As has been indicated above, the retaining plate 21, and the channel 43 which it supports, are supported in cantilever fashion, and hence it is desirable to prevent the accidental displacement thereof relative to the casing, or failure of the means attaching the same to the cas-

ing, due to the free end thereof engaging some object when the device is not in use. To this end it will be noted in Figs. III and IV that the width of the bottom wall 1d of the casing is slightly less than the overall width thereof and that the lower outer edges of the walls 1a are recessed to provide grooves 44 between the wall 1d and the lower outer edges of the walls 1a. The overall width of the channel retaining plate 21 is the same as that of the wall 1d and this plate and the channel member 43 are protected against damage, when the device is not in use, by means of a closure clip or guard 45 in the form of an upwardly directed channel member, the legs 46 of which have inwardly turned free edge portions 47 slidably received in the grooves 44. Also in inactive condition of the apparatus, with operating arm 8 depressed into contact with upper surface 1c of wall structure 1b, a group 16 of perforating pins projects through grid 19 and tends to project also through matching grid 22. The provision of guard 45 thus serves also to protect those punching pins against injury when the device is carried in a pocket or purse.

Operating arm 8 preferably carries a sliding latch 48 which serves to engage the operating arm to a retaining plate 48a between side walls 1a of the casing against the resistance of spring 12 when the operating arm is in its inactive nested position on the upper surface 1c of wall structure 1b.

In operation, the guard 45 is removed, and assuming that it is a check on which the punching operation is to be performed, the check is inserted transversely between the bottom wall 1d of the casing and the retaining plate 21 and received in frictional engagement with and between the live roller 23 and the resiliently mounted idler roller 39. It is then adjusted by eye both transversely and longitudinally with respect to the apparatus for punching the first character which is selected. Thereafter the adjustment is automatic as successive characters are selected and punched. The arm 8 is actuated to punch the first selected character. By the movement of operating arm 8 which causes punching movement of wheel 4 pawl 28 is moved downwardly into a position behind one of the teeth of ratchet wheel 27, and on the upward movement thereof the pawl, at the proper time, engages the ratchet wheel thereby rotating the live roller 23 to move the check, in a substantially straight line, one step to the next spaced position. As the punching proceeds, the check is moved step-by-step between the punching of sequential selected characters. It readily will be seen that the elongate rollers and associated operating means give accurate predetermined spacing between the characters as well as positioning of the line of punching in the proper region of the check.

Modification in the means for operating the live roller 23 is shown in Fig. X of the drawings. As shown in this modification, the shaft 26' supporting the roller 23 is extended entirely through the wall 1b and the end thereof rigidly connected to a manually operable wheel 49. Thus, in addition to the automatic means for operating the live roller 23, the wheel 49 may be turned manually to move the roller 23 and therefore the check, or other piece of paper, to initially position the same, to provide double or triple spacing of characters without removing the check from the device, or to move the check in the event the ratchet mechanism fails. The audible clicking of the resilient brake 37 and/or the spring pressed

pawl 28 as a tooth on the ratchet wheel is passed thereby, will indicate each unit of spacing of the characters. All the elements of this modified structure except the shaft for the live roller and its associated wheel, may be and are to be considered as identical with corresponding parts shown in Figs. I to IX, inclusive, of the drawings.

It thus readily will be understood that the illustration and description of the structure herein disclosed are exemplary of the embodiment of my invention and numerous modifications in the form and arrangement of parts being possible without departing from the spirit of that invention, my invention herein is to be restricted only by the limitations contained in the claims 15 appended hereto.

This application is a continuation-in-part of my copending application Serial No. 691,907, filed August 21, 1946, which has matured into Patent No. 2,464,815, granted March 22, 1949, and the 20 device disclosed herein is in the nature of an improvement on the device disclosed in said copending application.

I claim as my invention:

1. Manually operable punching apparatus 25 comprising in combination with a casing, a punching wheel mounted for adjusting rotation and straight-line punching movement in said casing, a wheel-actuating lever pivotally mounted in the forward region of said casing and extended rearwardly thereof acting to cause punching movement of said wheel under manual operation, a spring arranged in opposition to said wheel-actuating lever and exerting thereon a resilient force to retract said wheel, perforating pins mounted in groups forming punching characters peripherally of said wheel, matching grids at the base of said casing between which a work-sheet to be punched lies and through which the said perforating pins pass; work-sheet-positioning means comprising a pair of work-sheet-contacting rollers between which the work-sheet is passed, a ratchet on one of said rollers, a one-way pawl yieldingly engaged with said ratchet and extended toward and connected with said wheel-actuating lever, and a lost motion connection between said pawl and said wheel actuating lever adjacent the rearward end of said lever to provide lost motion at the beginning of the roller actuating stroke of said pawl, said lost motion connection thus acting to rotate said roller with time delay providing clearance of said perforating pins from a work-sheet in said grid during resilient retraction of said punching wheel and to shorten the stroke of said pawl in both directions of its movement with the said lever.

2. Manually operable punching apparatus comprising in combination with a casing, a punching wheel mounted for adjusting rotation and straight-line punching movement in said casing, a wheel-actuating lever pivotally mounted in the forward region of said casing and extended rearwardly thereof acting to cause punching movement of said wheel under manual operation, a spring arranged in opposition to said wheel-actuating lever and exerting thereon a resilient force to retract said wheel; sheet-positioning means comprising a pair of sheet-contacting rollers between which the work-sheet is passed, a ratchet on one of said rollers, an elongate one-way pawl yieldingly engaged with said ratchet and extended toward and connected with said wheel-actuating lever in a recess of said casing arranged rearwardly of said punching wheel, and a lost motion connection between said pawl and said wheel-

10 15 20 25 30 35 40 45 50 55 60 65 70 75

actuating lever adjacent the rearward end of said lever to provide lost motion at the beginning of the roller actuating stroke of said pawl, said lost motion connection thus acting to rotate said roller with time delay providing clearance of said perforating pins from a work-sheet acted on by said rollers during resilient retraction of said punching wheel and to shorten the stroke of the said pawl during both directions of its movement with the said lever.

3. Manually operable punching apparatus comprising in combination with a casing, a punching wheel mounted for adjusting rotation and straight-line punching movement in said casing, a wheel-actuating lever pivotally mounted in the forward region of said casing and extended rearwardly thereof acting to cause punching movement of said wheel under manual operation, a spring arranged in opposition to said wheel-actuating lever and exerting a resilient force to retract said wheel, perforating pins mounted in groups forming punching characters peripherally of said wheel, matching grids at the base of said casing between which a work-sheet to be punched lies and through which the said perforating pins pass; work-sheet-positioning means comprising a pair of work-sheet-contacting rollers between which the work-sheet is passed, a ratchet on one of said rollers, a one-way pawl yieldingly engaged with said ratchet and extended toward and connected with said wheel-actuating lever, said pawl being constructed to provide lost motion at the beginning of the roller actuating stroke thereof and thus acting to rotate said roller with time delay providing clearance of said perforating pins from a work-sheet in said grid during resilient retraction of said punching wheel.

4. Manually operable punching apparatus comprising in combination with a casing, a punching wheel mounted for adjusting rotation and straight-line punching movement in said casing, a wheel-actuating lever pivotally mounted in the forward region of said casing and extended rearwardly thereof acting to cause punching movement of said wheel under manual operation, a spring arranged in opposition to said wheel-actuating lever and exerting thereon a resilient force to retract said wheel; work-sheet-positioning means comprising a pair of work-sheet-contacting rollers between which the work-sheet is passed, a ratchet on one of said rollers, and an elongate one-way pawl yieldingly engaged with said ratchet and extended toward and connected with said wheel-actuating lever in a recess of said casing arranged rearwardly of said punching wheel, said pawl being constructed to provide lost motion at the beginning of the roller actuating stroke thereof and thus acting to rotate said roller with time delay providing clearance of said perforating pins from a work-sheet acted on by said rollers during resilient retraction of said punching wheel.

5. In a manually operable punching apparatus the combination of a casing, a punching wheel, means mounting said wheel in said casing for adjusting rotation and for straight-line punching movement as a whole with respect to said casing, perforating pins forming punching characters fixed in groups on the periphery of said punching wheel, a face of said wheel being provided with guiding ways extended radially thereof in guiding relation to the said several groups of perforating pins a distance at least equal to the bodily straight-line punching movement of said wheel, a guiding element fixedly mounted on

said casing in selective alignment with said guiding ways and arranged to enter and ride in said ways to guide and prevent rotation of said wheel during its straight-line punching movement, a perforated support associated with said casing and spaced below said pins and guiding element and adapted to receive said pins in their punching movement; work-sheet-positioning means comprising a pair of work-sheet-contacting rollers between which the work-sheet is passed, a ratchet on one of said rollers, and a one-way pawl yieldingly engaged with said ratchet and operatively connected with the said punching wheel to rotate said ratchet on retraction of the said punching wheel from punching position, said pawl being constructed to provide lost motion at the beginning of the roller actuating stroke thereof and thus acting to rotate said roller with time delay providing clearance of said perforated pins from a work-sheet in said perforated support during retraction of said punching wheel. 20

6. In manually-operable punching apparatus the combination of a casing, a punching wheel mounted in said casing for adjusting rotation and straight-line punching movement therein, a resilient guiding element positioned in the path of rotation and the path of punching movement of said wheel and arranged to engage with the wheel to deter rotation of the wheel and to guide punching movement of the wheel, resilient means 25 arranged yieldingly to oppose punching move- 30

ment of the wheel and to free the wheel of engagement with the said guiding element for adjusting rotation of the wheel; work-sheet-positioning means comprising a pair of work-sheet-contacting rollers between which the work-sheet is passed, a ratchet on one of the said rollers, and a one-way pawl yieldingly engaged with said ratchet and operatively connected with the said punching wheel to engage the ratchet and rotate the roller upon retraction of the punching wheel under the influence of the said resilient means, said pawl being constructed to provide lost motion at the beginning of the roller actuating stroke thereof and thus acting to rotate said roller with time delay providing clearance of said perforating pins from a work-sheet acted on by said rollers during resilient retraction of said punching wheel. 15
